Inventor:
Lewis Crawford Abraham
BY *L. C. Abraham* Attorney:

UNITED STATES PATENT OFFICE

LEWIS CROWFORD ABRAHAM, OF AUDERGHEM, BELGIUM

ARTIFICIAL SPONGE AND DEVICE FOR MANUFACTURING SAME

Application filed October 8, 1930, Serial No. 487,352, and in Belgium October 14, 1929.

My present invention relates to artificial sponges for cleaning kitchen utensils and other similar purposes and it has for its object to provide an improved sponge of this type formed of a bag made of gauze and stuffed with any suitable filling material.

In artificial sponges of this type the opening of the bag is usually closed by means of a wire inserted through the meshes of the gauze and tightened in order to draw the rims of said opening close together. The ends of said wire section are usually twisted together in order to prevent the mouth of the bag from being opened accidentally. The method of making such a closure, as well as the closure itself, is objectionable in many respects.

The making of the closure requires comparatively much time and skill. The closure itself is objectionable in that it is not very strong and the twisted ends of the closing wire section may easily hurt the user's hands.

My present invention has for its object to provide a sponge of the type described having a fixed closure, no dangerous unevenesses and a neater appearance than sponges closed by means of wire sections.

Broadly stated my invention consists in providing a cap for closing the mouth of the bag, the rim of said mouth previously drawn close together being housed within said cap. I prefer to secure on the sponge by means of teeth formed on it and engaging the meshes of the sponge but I do not desire to limit myself to this embodiment.

In the accompanying drawing:

Figs. 1 to 3 are diagrammatical views of different steps of the sponge bag closing operation.

Fig. 4 shows the finished sponge with its closing cap.

Fig. 4a shows a closing cap provided with a handle.

The first step of my improved method consists in drawing the rims of the opening 1 of

the sponge shaped wire gauze 2 close together. The metal gauze forming the sponge is cut from a wire gauze tube in the shape of a sleeve drawn together in the shape of a ball and turned inside out to form a bag, 50 the bottom 3 of which is closed inside by means of a wire section or the like. From Figs. 1 and 2 it will be seen how the opening 1 of said bag may be contracted to form a neck 5 by means of several radially arranged 55 moving fingers 4 whose points 17 engage the wire gauze near its edge.

In the second step of my method a cap 6 provided with a crown of teeth 7 will be placed upon the collar 5. The teeth 7 will be bent inwardly to cause the same to engage the collar 5 as shown in Fig. 3. To this end I use a plunger 8 which in its upward movement will press the cap 6 against the ends of the fingers 4 moved close together, whereby the teeth 7 engaging the curved faces 9 on the fingers 4 will be bent inwardly at right angles to the ring of the cap.

In the finished sponge as shown in Fig. 4 the rounded part of the cap only is visible 70 and forms an ornament which is for instance convenient for printing a trade mark or any advertisement thereon.

The cap 6 may also be provided with a handle 6a as shown in Fig. 4a, enabling the 75 sponge to be easily grasped. Said handle 6a may be attached to the cap 6 in any desired way.

Having now fully described my said invention, what I claim and desire to secure 80 by Letters Patent, is:

1. A scouring device comprising an elastic body, a cover of wire gauze for the elastic body, the edge of the wire gauze being drawn together to enclose the elastic body, and a cap closing the opening in the cover and having an annular series of prongs projecting into the edge of the cover and crimped toward the center of the cap to secure the edges of the gauze together.

2. A scouring device comprising an elastic body, a cover of wire gauze for the elastic body, the edge of the wire gauze being drawn together to enclose the elastic body, and a concavo-convex cap closing the opening in the cover and having prongs projecting into the edge of the cover and crimped toward the center of the cap to secure the edge of the gauze together, the cap and crimped edge of the gauze being forced upwardly into the elastic body, whereby the outer contour of the cap is substantially the same contour as the gauze.

LEWIS CROWDORF ABRAHAM.
